(57) **CLAIM**

The ornamental design for a mounting panel for an audio-video assembly, as illustrated and described.

DESCRIPTION

FIG. 1 is a front perspective view of my new design for a mounting panel for an audio-video assembly;

FIG. 2 is a front perspective view thereof;

FIG. 3 is a rear perspective view thereof;

FIG. 4 is a front elevational view thereof;

FIG. 5 is a left plan view thereof;

FIG. 6 is a right plan view thereof;

FIG. 7 is a top plan view thereof;

FIG. 8 is a bottom plan view thereof;

FIG. 9 is a rear elevational view thereof;

FIG. 10 is a front exploded perspective view thereof; and,

FIG. 11 is a rear exploded perspective view thereof.

The broken lines showing of a cabinet, an audio-video assembly and associated cabling is included for the purpose of illustrating environment and forms no part of the claimed design.
